FOREIGN PATENT DOCUMENTS

EP 1064876 B1 3/2005

Primary Examiner — Wan Laymon*Assistant Examiner* — Mark Booker(74) *Attorney, Agent, or Firm* — Boyle Fredrickson S.C.(57) **CLAIM**

The ornamental design for a roll towel dispenser lockout, as shown and described.

DESCRIPTION

FIG. 1 is a perspective view of a roll towel dispenser lockout incorporating our new design, viewed from in front of, above, and from the left side thereof;

FIG. 2 is an exploded perspective view thereof viewed from in front of, above, and from the left side thereof;

FIG. 3 is an exploded perspective view thereof viewed from in front of, above, and from a right side thereof;

FIG. 4 is a left side elevation view thereof;

FIG. 5 is right side elevation view thereof;

FIG. 6 is an exploded front elevation view thereof;

FIG. 7 is an exploded rear elevation view thereof;

FIG. 8 is an exploded top plan view thereof; and,

FIG. 9 is an exploded bottom elevation view thereof.

The dash broken lines shown in the figures represent portions of the roll towel dispenser lockout that form no part of the claimed design. The dash dot dash broken lines shown in FIGS. 1-4 represents boundaries to the claimed design and form no part of the claimed design.
